CIGARETTE HOLDER AND ASH RECEPTACLE

Hal W. Dahl, Chicago, Ill.

Application May 6, 1950, Serial No. 160,567

2 Claims. (C. 131—175)

This invention relates to cigarette holders in the class of holders through which cigarettes are smoked, and more particularly to cigarette holders combined with trough type ash receptacles into which the cigarette ashes fall.

In using such combinations as have been heretofore introduced in this category constant attention must be given to keeping the device turned so that the receptacle is kept positioned under the cigarette being smoked.

It is a primary object of this invention to provide a device in this general class, in which the ash receptacle automatically remains suspended in the best ash receiving position, without regard to the axially rotated positions of the cigarette holder structure with which it is embodied.

It is an important object to provide an ash receptacle of this character with a somewhat broad floor which serves as a supporting base to be instantly and safely rested on a chair arm, table, or other flat horizontal surface, as desired.

It is a further object to provide a receptacle of this class having upwardly directed sidewalls which incline toward each other from the receptacle bottom to prevent ashes from spilling therefrom when the receptacle is inadvertently tilted, and at the same time provide side walls, the upper portions of which flare apart to provide adequate means for catching the ashes as they fall from the cigarette.

It is also an object to provide a device in this class which is adapted to modern methods and facilities of economical manufacture.

The above and other objects are attained by the construction shown in the accompanying drawing of which:

Fig. 1 is a sectional view taken in the proximity of line 1—1 of Fig. 5;

Fig. 2 is a partial perspective detail sectional view taken on line 2—2 of Fig. 1;

Fig. 3 is a partial perspective detail sectional view taken on line 3—3 of Fig. 1;

Fig. 4 is a perspective view of the receptacle unit taken on line 4—4 of Fig. 1;

Fig. 5 is a sectional view taken in the proximity of line 5—5 of Fig. 1; and

Fig. 6 is a perspective view of an individual part taken on line 6—6 of Fig. 1.

Similar characters of reference designate similar parts throughout the different views.

Referring to Fig. 1, the numeral 1 designates a cigarette holder bit or mouth piece of conventional styling. In the normally forward end of said bit, the cylindrical cigarette supporting socket 2 is formed coaxially therein and said socket is adapted to receive one end of an ordinary cigarette which may be conveniently pressed into same so that it serves to support such cigarette in smoking position as indicated by dot-and-dash lines 3. Said socket communicates with the usual smoke hole 4 which extends from same through said bit longitudinally thereof, as will be understood in the art. Said forward end is reduced in size forming a forwardly extending spindle 5, with a shoulder 6 and is concentric with said socket. A metal band 7 is inlaid around the forward extremity of said spindle for stability.

The two identical or similar sleeves 8 are coaxial on the spindle 5, being frictionally retained thereon by press

bit relation therewith. Each of said sleeves has an outwardly disposed flange 9 at one end, the other end of each being plain. These sleeves are oppositely arranged on said spindle with their plain ends abutting, and their flanges spaced considerably apart so that each end of said spindle is encircled by one of said flanges. One of said sleeves is illustrated in perspective in Fig. 6. Considered together said sleeves constitute a spool-like structure with said spindle, by reason of the spaced arrangement of their flanges.

Two spaced coaxial rings 10 are provided and each pivotally encircles one of the sleeves 8 adjacent the respective flange 9. Said rings are secured by solder or otherwise at their normally lower points to the substantially horizontal flange wall 11 as shown in Fig. 2 which is integral with and transverse to the normally vertical weight head 12 from the upper edge of which said flange wall extends forwardly. Said rings are secured tangentially to said flange wall by soldering in this example, although it is understood that other appropriate securing means may be used. The rings 10 are free to rotate on the sleeves 8 and thus pivotally suspend as a unit, the weight head 12 together with its flange wall 11, its side flange walls 13 and floor supporting flange wall 14 all of which will be again referred to, and that said rings are confined along the axial line of said sleeves by their flanges 9 and are thus retained thereon.

The weight of the weight head 12, combined with the weight of the aforesaid flange walls, will by force of gravity reduce the rotation or oscillation of the rings 10 with the sleeves 8 when the bit 1 is casually or otherwise rotated or oscillated about its axis. In the beginning of the smoking operation when the device is picked up with the weight head 12, and its said flange walls at a random rotated position as a unit with the rings 10, said unit will be brought to and kept in a plumb working position by force of gravity as soon as the bit 1 is brought to an operating position which will be more or less horizontal, the rings 10 oscillating on the sleeves 8 correspondingly.

The weight head 12 has an inverted keystone contour and the above mentioned side flanges 13 extending integrally and forwardly from said side edges also slant upwardly accordingly from the ends of the floor supporting flange wall 14 which extends integrally and forwardly from the lower edge of said weight head substantially parallel with the flange wall 11, so that the said flange walls together with said weight head form a forwardly open hollow structure adapted to enclose and support the aft end of the ash receptacle which rests directly on said floor supporting flange wall, the aft ends of the inclining side walls 15 of said receptacle being overlapped by the flange walls 13 which incline accordingly.

From the inner edges of the receptacle walls 16, from points immediately forward of the weight head 12 to the other end of said walls, the flared walls 18 extend upwardly and apart as continuations thereof, and together serve as a trough-like funnel into which ashes from a cigarette being smoked may fall and be thus directed to the receptacle floor 17.

The fore end of the receptacle formation is closed by the end plate 19, said plate having a flange 20 which overlaps the fore end regions of the receptacle walls 16 and 18 and floor 17, said flange also having a portion which arches upwardly between the walls 18, and thus serves to catch the cigarette ashes when the device is tilted forwardly to an extreme position, and direct the same to the receptacle floor 17.

From the foregoing it will be obvious that when the invention is used at practically any working angle, the cigarette ashes will be directed to the receptacle floor with practically no danger of falling otherwise, and making it unnecessary to shake the ashes off in an independent

tray. It will also be seen that because of the convergingly inclined character of the walls 16, the device, even if tilted considerably by accident, as suggested by dotted lines 21 of Fig. 5, will operate to confine the ashes in the receptacle.

It will also be obvious that the invention may be rested on its floor supporting flange 14 and corresponding part of the flange 20, when placed on any flat surface such as that of a table within convenient reach of the user, and that when thus rested upon a soft or irregular surface the floor 17 coordinates with said flanges as a supporting base.

The weight head 12 is preferably constructed of one of the heavier metals, and it will be noted that the walls thereof are of sufficient thickness to provide ample weight for keeping same suspended below the bit spindle 5, through the pivotal relation of the rings 10 on the sleeves 8, it being understood of course that in addition to the weight of said weight head, the weight of the remainder of the receptacle coordinates with said weight head in positioning the receptacle as an entirety.

As before mentioned the flanges 9 of the sleeves 8 are spaced considerably apart, the plain ends of said sleeves abutting as illustrated in Fig. 1, and each of the rings 10 being adjacent one of said flanges, are accordingly spaced apart in order that they will together establish a journal of sufficient length along its axis to stably support the aforementioned forwardly overhanging ash receptacle with its end plate 19. Said receptacle is thus pivotally supported for free rotation on said spindle and sleeves in said rings which are spaced far enough apart to prevent sagging of the forward end of same.

The invention may be assembled in different ways. The ash receptacle may be first, connected with the bit 1 by means of the sleeves 8 and rings 10 by first inserting each of the two sleeves through one of said rings so that the plain ends of said sleeves come together. The spindle 5 is then pressed into said sleeves the rearward one being entered first; or one of said sleeves may be selected as the rearward one and pressed onto said spindle with its flange end against the shoulder 6. Said spindle is then inserted through the rings 10, bringing the already assembled sleeve within the rearward ring. The forward sleeve is then pressed onto said spindle and at the same time into the forward ring.

While the invention has been described in conjunction with the accompanying drawing, it is understood that it is not entirely restricted to the example shown, but that variations may be made without departing from the scope of the appending claims.

The invention claimed is:

1. A cigarette holder and ash receptacle combined

comprising a bit, and an elongated ash receptacle extending forwardly beyond said bit, said receptacle having an end and weight element combined and a pivotal construction serving to pivot said element to said bit in receptacle operating relation therewith, said construction consisting of a sleeve means fixed around the forward end of said bit co-axially therewith, said sleeve means having flanges spaced apart, and a receptacle supporting ring means encircling said sleeve means between said flanges and being free to rotate thereon, said ring means being fixed to said element, and the overall axial length of said ring means, considered along the axis of said sleeve means, being sufficient to alone hold said receptacle substantially parallel to said axis.

15 2. A cigarette holder and ash receptacle combined comprising a bit, an elongated and forwardly pivotally depending ash receptacle having a horizontal floor wall and side walls all of which extend beyond said bit and having a hollow aft end element with walls which overlap
20 said floor and side walls and together surround the aft ends of the same, a mechanism pivotally suspending said end element from said bit in receptacle supporting relation said mechanism consisting of a sleeve means fixed around the forward end of said bit coaxially therewith
25 said sleeve means having retaining flanges, and a free fitting ring means which encircles said sleeve means and is retained on the same by said flanges said ring means being mounted on said end element and the overall length of said ring means considered along said bit adapting same to
30 hold said receptacle substantially parallel to the longitudinal axis of said bit.
